UNITED STATES PATENT OFFICE.

CORA ISABEL KYLE, OF ALTAMONT, ILLINOIS.

DESIGN FOR A RECITATION-BOARD.

46,745.

Specification for Design.

Patented Dec. 8, 1914.

Application filed October 1, 1914. Serial No. 864,538. Term of patent 7 years.

To all whom it may concern:

Be it known that I, CORA ISABEL KYLE, a citizen of the United States, residing at Altamont, in the county of Effingham and State of Illinois, have invented a new, original, and ornamental Design for a Recitation-Board, of which the following is a specification, reference being had to the accompanying drawing, forming a part thereof.

Figure 1 is a front perspective view of

a recitation board of the design of this invention. Fig. 2 is a rear perspective view of the same.

I claim:

The ornamental design for a recitation board as shown.

CORA ISABEL KYLE.

Witnesses:

Mrs. P. L. PETZING,
MARTHA M. HELMBACHER.
